INKER

Charles W. Harrold and Henry F. Meyer, University Heights, Ohio, assignors to Harris-Seybold Company, a corporation of Delaware

Application September 5, 1942, Serial No. 457,494

25 Claims. (Cl. 101—349)

1 This invention relates to improvements in inkers for printing presses. In some of its aspects it relates particularly to inkers for printing presses employing a form cylinder having a gap in its periphery which gives rise to a periodic interruption of the contact of the form inking rollers with the form.

It is a general object of the invention to provide an inker which is simple and economical in construction and efficient in distributing ink and applying it to the printing plate.

Another object is the provision of simplified means for driving and reciprocating the vibrating rollers of the inker.

Another object is the provision of an inker having rollers of relatively small diameter only, wherein the first ink taken from a common distributing roller is conducted to a set of form rollers positioned to make contact first with the plate on the plate cylinder and wherein the second charge of ink taken from the said common distributing roller is conducted along a path providing additional working of the ink to a set of form rollers positioned to make contact with the plate after its contact with the first set, the second set functioning to smooth out and equalize the ink applied by the first set.

Another object of the invention is the provision of means for improving the uniformity of inking of the form.

Still another object is the provision of means for interrupting the transmission of ink to certain form rollers for a period corresponding to the passage of the gap in the plate cylinder beneath those form rollers.

Other objects and features of novelty will appear as we proceed with the description of that embodiment of the invention which, for the purposes of the present application, we have illustrated in the accompanying drawings, in which

Fig. 1 is a fragmental, elevational view of an offset printing press having an inker embodying the present invention;

Fig. 2 is a fragmental end elevational view partly in section along the line 2—2 of Fig. 1;

Fig. 3 is a diagrammatic, elevational view looking toward the opposite side of the machine from that illustrated in Fig. 1;

Fig. 4 is a fragmental, diagrammatic view partially in section on the line 4—4 of Fig. 5, the center line A—A of the figure being shifted from its position of Fig. 3 for the sake of convenience;

Fig. 5 is a fragmental plan view partially in section on the line 5—5 of Fig. 4; and

Fig. 6 is a detailed, elevational view showing

2 cam means for momentarily separating certain rollers in the ink paths.

In the drawing one of the side frame members of an offset printing press is shown at 10. The machine comprises a similar frame member at the opposite side. Frame members 11 for the inker are attached to the frame members 10 and, in effect, constitute continuations thereof. The inker frame members carry bearings for a series of vibrating rollers 12, 13, 14, 15, and 16, of which the rollers 15 and 16 are storage rollers. These rollers have shafts which are adapted to slide as well as to revolve in their bearings, and outside one of the frame members 11 these shafts carry spur gears 17, 18, 19, 20, and 21, all of which mesh with a wobble gear 22, the hub of which is fixed upon a shaft 23 which is rotatably mounted in the frame members and rotatably carries an ink transmitting roller 24 which is driven by frictional contact with adjacent rollers.

The web of wobble gear 22 is inclined to the axis of shaft 23 but the teeth of the gear are parallel to that axis. The sides of the gear are bevelled as indicated at 25 for engagement with bevelled surfaces on disks 26 which are clamped to the opposite sides of gears 17, 18, 19, 20, and 21 and form, in effect, flanges for those gears. The disks therefore turn with the spur gears, and their engagement with the bevelled surfaces of the wobble gear causes the vibrating rollers to reciprocate. Hence the rotation and reciprocation of the vibrating rollers are accomplished by a single set of gears. As illustrated, the vibrating rollers are all of the same diameter and their axes intersect a circle 27 with its center at the axis of gear 22, and this has an advantage from the standpoint of economy in manufacturing and servicing, but it is not essential that the vibrating rollers be of the same size. They can be of different sizes, in which event their axes will be arranged around the center of gear 22 and at the proper distance away. The gearing preferably is such that all the driven rollers have the same surface speed as that the plate cylinder.

45 The wobble gear 22 is seen to perform two functions. The web of this gear, being inclined to the axis of shaft 23, acts as a wobble plate to reciprocate the vibrating rollers, while the teeth of the gear are parallel to shaft 23 and act to rotate these rollers.

In addition to the vibrating rollers and the non-vibrating friction driven roller 24, the inker frame members carry in conventional mountings ink distributing rollers 30, 31, 32, 33, 34, and 35 which are composition rollers, and also com-

position form rollers 36, 37, 38, and 39, all of which composition rollers are driven by frictional contact with adjacent rollers. The form rollers are adapted to contact the plate 40 on the plate cylinder 41, and they contact in pairs the storage rollers 15 and 16. A ductor roller 42 swings back and forth between vibrating roller 12 and a roller in the ink fountain 43 in the usual or conventional manner. Dampening rollers 44 and 45 take moisture from a roller 46 which receives it from a ductor roller 47 that engages intermittently with a roller 48 of a water fountain, this dampening mechanism being of any suitable known construction.

One of the features of our invention is the provision of means for periodically breaking connection between the rollers 32 and 15 and between the rollers 35 and 16. The mechanism employed for the purpose will now be described. At opposite sides of the machine just within the frame members 11 there are brackets 50 which are alike except as to rights and lefts. These brackets are threaded to take screws 51 which are arranged by sleeves 52 slightly longer than the thickness of frame members 11. These sleeves are movable vertically in slots provided in the frame members. Brackets 50 have U-shaped cavities 53 in which the reduced ends 54 of roller 35 rest and are journaled. Somewhat above the cavities 53 the inner faces of the brackets are provided with inclined slots 55 for the reception of the reduced ends 56 of roller 34. On one side of each of these brackets there is a lug 57 having a tapped hole in which is mounted an adjusting screw 58 that bears at its lower end against a lever 59 which is pivotally mounted upon a stud 60 carried by the frame. It will be understood that there are two such levers, one at each side of the press.

Each of a second pair of brackets 61 positioned just inside the frame members is threaded to receive a screw 62 surrounded by sleeve 63 of the same length as sleeve 52, the sleeve 63 being received by a hole 64 in the frame member of considerably larger diameter than the external diameter of the sleeve. Brackets 61 have U-shaped sockets 65 for the reception of the reduced ends 66 of roller 32. They are also provided on their inner faces with inclined slots 67 in which are received the reduced ends 68 of roller 33. Each of the brackets 61 has an inwardly extending lug 69 in which there is a tapped hole for an adjusting screw 70 similar to screw 58. The lower end of screw 70 bears against the outer end of a lever 71 that is pivotally mounted on a stud 72 carried by the frame. In each of the studs 72 and each of the brackets 61 are formed sockets for the reception of compression springs 73, by means of which the lower ends of the brackets 61 are biased toward the right, holding the roller 32 resiliently but yieldably against the rollers 15 and 14.

On the inner ends of levers 59 and 71 there are mounted roller followers 74 and 75, respectively, which bear against cams 76 and 77 that are fixed to the shaft 23. It will be apparent that as shaft 23 turns, levers 71 will be rocked to raise and lower brackets 61 and that levers 59 will be similarly rocked to raise and lower brackets 50. The upper ends of the brackets at each side of the machine are biased toward each other by tension springs 78. Roller 35 most of the time rests upon roller 16, and when raised, as shown in Fig. 4, it rests in the U-shaped sockets 53 of brackets 50. Roller 32 rests upon roller 15

except when brackets 61 are raised. At all times roller 32 is maintained in engagement with roller 14 by compression springs 73. When brackets 61 are raised by levers 71, springs 73 yield to permit roller 32 to ride diagonally upward along the surface of roller 14, which of course raises roller 33, the latter being maintained in engagement with roller 24, however, by the springs 78. Both pairs of movable rollers are returned to their lower normal position by gravity when the followers 74 and 75 ride off the high spots of cams 76 and 77.

The inker is driven by an endless chain 81 that runs over a sprocket 82 on the blanket cylinder of the press and over a sprocket 83 secured to the hub of the wobble gear 22. All of the vibrating rollers are thus positively driven, and the remaining rollers are driven by friction. The dampening rollers 44 and 45 are driven by frictional contact with the roller 46, which in turn is driven by gearing meshing with a large gear 84 on the plate cylinder, the latter in turn meshing with a large gear 85 on the blanket cylinder 86. The impression cylinder 87 also carries a large gear 88 which meshes with gear 85. Power is transmitted by suitable means, not shown, from a drive pulley 89 to the blanket cylinder, from which the rest of the machine is driven.

Operation.—Ink travels from ink fountain 43 over the surfaces of rollers 42, 12, 30, 13, and 31 to vibrating roller 14, which is always in engagement with distributing roller 32. Ink taken off of roller 14 by roller 32 is delivered first to storage roller 15 and thence to form rollers 31 and 36. The second delivery of ink from roller 32 goes to roller 33 and thence over rollers 24, 34, 35, and 16 to form rollers 39 and 38. Hence a greater but less evenly mixed charge of ink is ordinarily transmitted to the plate 40 form rollers 37 and 36 than from form rollers 39 and 38, and the latter rollers, carrying a less quantity of more thoroughly mixed ink, act partially for smoothing out and equalizing ink then on the plate.

A portion of the water or other plate dampening fluid which is placed upon the plate by rollers 44 and 45 finds its way up into the inker from the form rollers, thereby diluting the ink and affecting to some extent the shade or degree of color in the printing. Periodically, however, the passing of the gap 80 of the plate cylinder beneath the form rollers interrupts the transmission of dampening fluid to the form rollers, and for a corresponding period reduces the dilution of the ink on the form rollers and on the storage rollers 15 and 16. In the conventional machine this sometimes results in a zone of printing near the front edge of each sheet which is somewhat darker in shade than in the balance of the sheet. This difficulty is overcome in our invention by the described mechanism for momentarily separating rollers 32 and 35 in succession from the storage rollers 15 and 16.

While the gap 80 is passing form roller 36, for example, that roller receives no dampening fluid, and that portion of the surface of roller 36 which receives no dampening fluid transmits none to storage roller 15. The parts are preferably so timed that when the forward edge of the undampened zone of roller 15 is on the point of engaging roller 32, the latter roller is lifted so that no additional ink is transmitted to that part of the surface of roller 15 which is "dry," relatively speaking. As soon as the "dry" zone has passed, the roller 32 is permitted to descend

again. In this manner equalization of color in printing is maintained.

Since conditions vary from time to time and since the relationship of the cylinder gap and diameters of the inking rollers may vary, the cams 76 and 77 are preferably, and as shown, adjustably secured to shaft 23 to permit changing the timing of the interruption of contact between the rollers in order to best compensate for any unevenness of application of ink.

Although the invention is illustrated in connection with a lithographic press, the various features, including the interruption of the transmission of ink to the form rollers, are applicable to other types of printing presses.

Having thus described our invention, we claim:

1. In an inker for a printing press, a plurality of parallel vibrating rollers, a gear on each of said rollers, an ink transmitting roller surrounded by said vibrating rollers, means for driving said ink transmitting roller, a wobble gear concentric with said last-named roller meshing with and driving each of said first-named gears, and interengaging means on said wobble gear and each of said first-named gears for reciprocating the vibrating rollers.

2. In an inker for a printing press, a driven shaft, a series of positively rotated and reciprocated rollers including two storage rollers arranged around said shaft, driving means for said rollers mounted on said shaft, means on each of said rollers cooperatively engaging said driving means to effect rotation and reciprocation thereof, roller means providing an ink path from each of said storage rollers to the plate of the printing press, and roller means arranged to provide an ink path from one of said storage rollers to the other including a roller rotatably mounted on said driving shaft.

3. In an inker for a printing press, a plate cylinder, a pair of storage rollers, form rollers in contact with each of said storage rollers adapted to deliver ink to said plate cylinder, a distributing roller adapted to contact with each of said storage rollers for feeding ink to the latter, and means for momentarily separating each of said distributing rollers from the corresponding storage roller once for each revolution of the plate cylinder.

4. In an inker for a printing press, a plate cylinder having a gap, a pair of storage rollers, form rollers in contact with each of said storage rollers adapted to deliver ink to said plate cylinder, a distributing roller adapted to contact with each of said storage rollers for feeding ink to the latter, and means for periodically separating each of said distributing rollers from the corresponding storage roller in predetermined relation to the time of passage of the gap in the plate cylinder over the form rollers associated with that storage roller.

5. In an inker for a printing press, a plate cylinder having a gap, a pair of storage rollers, form rollers in contact with each of said storage rollers adapted to deliver ink to said plate cylinder, a distributing roller adapted to contact with each of said storage rollers for feeding ink to the latter, and individually functioning means for separating each of said distributing rollers from the corresponding storage roller in predetermined relation to the time of passage of the gap in the plate cylinder over the form rollers associated with that storage roller.

6. In an inker for a printing press, a plate cylinder having a gap, a pair of storage rollers, form

rollers in contact with each of said storage rollers adapted to deliver ink to said plate cylinder, a distributing roller adapted to contact with each of said storage rollers for feeding ink to the latter, and two cam mechanisms functioning individually in succession for separating each of said distributing rollers from the corresponding storage roller in predetermined relation to the time of passage of the gap in the plate cylinder over the form rollers associated with the respective storage rollers.

7. In an inker for a printing press, a plate cylinder having a gap, a pair of storage rollers, form rollers in contact with each of said storage rollers adapted to deliver ink to said plate cylinder, a distributing roller adapted to contact with each of said storage rollers for feeding ink to the latter, a cam shaft between said distributing rollers, two cams on said shaft, and means actuated by said cams for separating each of said distributing rollers from the corresponding storage roller in predetermined relation to the time of passage of the gap in the plate cylinder over the form rollers associated with the respective storage rollers.

8. In an inker for a printing press, a plate cylinder, two storage rollers, form rollers between the storage rollers and the plate cylinder adapted to be contacted in succession by a given point on the surface of the plate cylinder, an ink transmitting roller, distributing rollers including a roller between said transmitting roller and each of said storage rollers, certain of said distributing rollers being in contact with said storage rollers, and means independent of said transmitting roller for delivering ink to one of said distributing rollers which is in contact with the storage roller associated with the form roller first contacted by a given point on the surface of said plate cylinder.

9. In an inker for a printing press, a plate cylinder, two storage rollers, form rollers between the storage rollers and the plate cylinder adapted to be contacted in succession by a given point on the surface of the plate cylinder, an ink transmitting roller, distributing rollers including a pair of rollers between said transmitting roller and each of said storage rollers, certain of said distributing rollers being in contact with said storage rollers, and means independent of said transmitting roller for delivering ink to one of said distributing rollers which is in contact with the storage roller associated with the form roller first contacted by a given point on the surface of said plate cylinder.

10. In an inker for a printing press, a plate cylinder, two storage rollers, form rollers between the storage rollers and the plate cylinder adapted to be contacted in succession by a given point on the surface of the plate cylinder, an ink transmitting roller, distributing rollers including two rollers only between said transmitting roller and each of said storage rollers, certain of said distributing rollers being in contact with said storage rollers, and means independent of said transmitting roller including a plurality of continuously rotating rollers for delivering ink to one of said distributing rollers which is in contact with the storage roller associated with the form roller first contacted by a given point on the surface of said plate cylinder.

11. In a printing press having a driven plate cylinder and a driven printing cylinder associated therewith, a series of positively driven ink rollers, a driven gear fixed on each of said rollers, a driv-

ing gear meshing with each of said driven gears, and means for transmitting driving force from said printing cylinder to said driving gear independently of said plate cylinder.

12. In an inker for a printing press, a plurality of parallel vibrating rollers, a gear on each of said rollers, an ink transmitting roller surrounded by said vibrating rollers, a wobble gear concentric with said transmitting roller meshing with and driving each of said first named gears, said transmitting roller being driven by surface contact from one of said vibrating rollers, and interengaging means on said wobble gear and each of said first named gears for reciprocating the vibrating rollers.

13. In an inker for a printing press, a plate cylinder, two storage rollers, form rollers between the storage rollers and the plate cylinder adapted to be contacted in succession by a given point on the surface of the plate cylinder, an ink transmitting roller, distributing rollers including at least one roller between said transmitting roller and each of said storage rollers, certain of said distributing rollers being in contact with said storage rollers, and means independent of said ink transmitting roller for delivering ink to one of said distributing rollers which is in contact with the storage roller associated with the form roller first contacted by a given point on the surface of said plate cylinder.

14. In an inker for a printing press, a plate cylinder, two storage rollers, a gear on each of the storage rollers, a driven gear meshing with and driving each of said first named gears, form rollers between the storage rollers and the plate cylinder adapted to be contacted in succession by a given point on the surface of the plate cylinder, an ink transmitting roller, distributing rollers including at least one roller between said transmitting roller and each of said storage rollers, an ink fountain, and roller means independent of said ink transmitting roller for delivering ink from the ink fountain to one of said distributing rollers which is in contact with the storage roller associated with the form roller first contacted by a given point on the surface of said plate cylinder, said roller means comprising a plurality of positively driven rollers and a gear on each of the latter meshing with and driven by said driven gear.

15. In an inker for a printing press, two storage rollers, form rollers between the storage rollers and the plate cylinder, an ink transmitting roller, at least one distributing roller between said transmitting roller and each of said two storage rollers, one of said distributing rollers being disposed on each side of a plane containing the axes of said ink transmitting roller and said plate cylinder, an ink fountain disposed on one side of said plane, and roller means independent of said ink transmitting roller for delivering ink from said fountain to that one of said distributing rollers which is disposed on the opposite side of said plane from said ink fountain.

16. In an inker for a printing press, a plate cylinder, two storage rollers, a gear on each of said storage rollers, a driven gear meshing with and driving each of said first named gears, form rollers between the storage rollers and the plate cylinder, an ink transmitting roller, at least one distributing roller between said transmitting roller and each of said two storage rollers, one of said distributing rollers being disposed on each side of a plane containing the axes of said ink transmitting roller and said plate cylinder, an ink fountain disposed on one side of said plane, and roller means independent of said ink transmitting roller for delivering ink from said fountain to that one of said distributing rollers which is disposed on the opposite side of said plane from said ink fountain.

ink fountain disposed on one side of said plane, and roller means independent of said ink transmitting roller for delivering ink from said fountain to that one of said distributing rollers which is disposed on the opposite side of said plane from said ink fountain, said roller means comprising a plurality of positively driven rollers and a gear on each of the latter meshing with and driven by said driven gear.

17. In an inker for a printing press, a plurality of positively rotated inking rollers, a gear on each of said rollers, driven rotary means for rotating and reciprocating said rollers comprising gear teeth meshing with said roller gears, an ink transmitting roller arranged with its axis within the pitch circle of said gear teeth and turning at an angular speed different from that of said gear teeth, and roller means between said ink transmitting roller and each of two of said inking rollers, whereby a path is provided for transmission of ink between said two inking rollers by way of said transmitting roller.

18. An inker for a printing press according to claim 17, wherein two of said inking rollers constitute storage rollers, and wherein form roller means is interposed between each of said storage rollers and the form of the printing press.

19. In an inker for a printing press, a series of positively rotated inking rollers two of which constitute storage rollers of said inker, form roller means for transmitting ink from each of said storage rollers to the form of the printing press, a gear on each of said inking rollers, a driven wobble gear meshing with and driving each of said first named gears, means on each of said inking rollers engaging said wobble gear for enabling said rollers to derive reciprocation from said wobble gear, an ink transmitting roller arranged with its axis within the pitch circle of said wobble gear, and roller means between said ink transmitting roller and each of said storage rollers, whereby a path is provided for transmission of ink between said storage rollers by way of said transmitting roller.

20. In an inker for a printing press, a series of positively rotated inking rollers, a gear on each of said rollers, a driven gear meshing with and driving each of said first named gears, an ink transmitting roller arranged with its axis within the pitch circle of said driven gear, and roller means between said ink transmitting roller and each of two of said inking rollers, said transmitting roller and said roller means being driven by surface contact from said two inking rollers, whereby a path is provided for transmission of ink between said two of said inking rollers.

21. Mechanism as claimed in claim 20, wherein said two inking rollers constitute storage rollers of said inker, and including form roller means for transmitting ink from each of said storage rollers to the form of the printing press.

22. In an inker for a printing press, a series of positively rotated inking rollers, a gear on each of said rollers, a driven rotating element including gear teeth meshing with and driving each of said first named gears for rotating said inking rollers, an ink transmitting roller arranged with its axis within the pitch circle of said gear teeth, roller means between said ink transmitting roller and each of two of said inking rollers, said transmitting roller and said roller means being driven by surface contact from said two inking rollers, whereby a path is provided for transmission of ink between said two of said inking rollers, and interengaging means on said driven rotating element

and said inking rollers for reciprocating the latter. 23. Mechanism as claimed in claim 22, where-
in said two inking rollers constitute storage rollers
of said inker, and including form roller means
for transmitting ink from each of said storage
rollers to the form of the printing press.

24. In an inker for a printing press, a group
of rollers comprising a series of positively rotated
inking rollers and an ink transmitting roller, com-
position rollers connecting each roller of said
group with at least one other roller of said group,
said ink transmitting roller being driven by sur-
face contact and being connected by certain of
said composition rollers for transmission of ink
from one of the rollers of said group to another
roller thereof, a gear on each of said positively
rotated rollers, a driven rotating element includ-
ing gear teeth meshing with and driving all of said
first named gears for rotating said rollers, and
interengaging means on said driven rotating ele-
ment and said inking rollers for reciprocating
the latter.

25. In an inker for a printing press, a plurality
of positively rotated inking rollers, a gear on each
of said rollers, driven means for rotating said roll-
ers comprising gear teeth meshing with said roller
gears, an ink transmitting roller arranged with

its axis within the pitch circle of said gear teeth
and turning at an angular speed different from
that of said gear teeth, and roller means between
said ink transmitting roller and each of two of
said inking rollers, whereby a path is provided
for transmission of ink between said two inking
rollers by way of said transmitting roller.
